UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed June 30, 1927. Serial No. 202,631.

This invention relates generally to improvements in web-manifolding typewriting machines, such as disclosed in the patent to Wernery & Smith, No. 1,132,055, dated 5 March 16, 1915.

Some offices require that two kinds of records be made of usual check-vouchers employed in paying certain expenses. One record usually consists of a set of record-forms 10 for each check-voucher, each form having a carbon-copied thereon all matter typed on a check-voucher, including the name and the address of the payee. The other record is usually a plurality of record-sheets, each 15 bearing a carbon-copy of a line of special record-data on each check-voucher.

It is an object of this invention to provide means for preparing the above-noted kinds of records of check-vouchers in a typewriting machine in an efficient manner while typing the original check-voucher. It is a further object to provide means for making a plurality of records, in condensed form, of the special record-data typed on the check- 25 vouchers.

In carrying out my invention, an Underwood typewriting machine of the Wernery-Smith type is provided with two separately movable carbon-carriers running on the same 30 track, one behind the other. The forward carbon-carrier holds carbons interleaved between the plies of a main web bearing a succession of check-voucher-forms, and the rear carbon-carrier holds carbons interleaved between the plies of a condensed record-web. The leading ends of all the carbons are evenly disposed above the printing line for typing the line of special record-data on the leading 35 check-voucher, and this line is manifolded on all the plies of both webs. After line-spacing both webs ahead one or more line-spaces as usual and then unlocking the platen and raising it a small amount, clamps mounted on the usual platen-displacing frame are operated to grip the condensed record-web 40 against a usual paper-table to hold it stationary while the operator pulls the typed line on the main web ahead to a web collating position. The platen is then locked down again, 45 the clamps are released and both webs are fed

rearwardly a predetermined amount by a condensing handle mechanism, which will bring the second line of writing on the check-voucher to the printing line and carry the leading edges of the carbons of the record-web below the printing line far enough to permit the name and the address of the payee and other matter to be typed on the original check-voucher and copied on the check-voucher web-plies without being carbon-copied on the record-web. The condensing handle mechanism may now be operated to rotate the platen forwardly one line beyond its position before being moved rearwardly, which will bring the lines of record-data on the record-web the desired distance above the printing line for usual condensed record-work. The clamps may now be made effective to grip the record-web again to hold it in position while the carbons are stripped and the first set of 55 check-voucher-forms is severed in the usual way from the body of the check-voucher-web. The clamps are then released and the succeeding check-voucher typed. 60

A feature of the present invention resides 65 in arranging the usual control lever for locking down the platen with a single notch having cam-faces effective for raising the platen a small amount to release the check-voucher-web from the grip of the platen and the lower feed-rolls preparatory to moving the web ahead. 70

Another feature resides in the provision 75 of a lateral blade normally held away from the usual paper-table and swingable rearwardly adjacent the paper-table for use both as a check-voucher collating-gage and a cutting-off knife. 80

Still another feature resides in the organization of parts for collating one work-web 85 relatively to the other, including two separately movable carbon-carriers, the record-web-holding clamps, and the means for concomitantly unlocking and raising the platen. 90

Other features and advantages will hereinafter appear. 95

In the according drawings,

Figure 1 is a fragmentary sectional view, front to rear, through an Underwood typewriting machine, embodying my invention, 100

the work-webs being shown in position for having typed thereon the first line of record-data on a check-voucher. The record-web is shown advanced in this view as it would ordinarily appear after having typed thereon in condensed form a large number of lines of record-data.

Figure 2 is a diagrammatic view, showing the work-webs line-spaced ahead subsequently to the typing of the first line of record-data, the clamps being shown in effective position for gripping the record-web preparatory to advancing the check-voucher web separately.

Figure 3 is a diagrammatic view, showing the relative positions of the work-webs after the check-voucher-web has been advanced, the record-web being held stationary by the clamps.

Figure 4 is a diagrammatic view, showing the carbons of the record-web moved to an ineffective position below the printing line by operation of the condensing handle mechanism. The check-voucher-web is shown positioned for receiving the second line of typing.

Figure 5 is a diagrammatic view, showing the record-web carbons advanced above the printing line after the typing of the check-voucher-form has been completed. The clamps are shown in effective position again.

Figure 6 is a diagrammatic view, showing two work-webs straightened out in carbon-stripping position, the check-voucher-web being pulled ahead to its cutting-off gage with the clamps still disposed in effective position.

Figure 7 is a diagrammatic view, showing the platen returned to normal typing position and the cutting-off knife moved rearwardly to effective cutting-off position, the carbons of both webs being left even and in position for copying the line of record-data on the next succeeding check-voucher-form on all the plies of both webs.

Figure 8 is a partial front diagrammatic view of the record-web in position around the platen with the overlying check-voucher-web disposed intermediate the sides of the record-web.

Figure 9 is a partial top view of the typewriting machine shown in Figure 1, certain parts being shown broken away and others in section to better illustrate the construction of the machine.

In a well-manifolding typewriting machine of the Wernery-Smith type, a type 10 may be swung by instrumentalities, not shown, up against a platen 11 having a shaft 12 journaled in a platen-displacing frame 13, pivotally mounted in a carriage 14. Feed-rolls 15 and 16 are supported by said carriage for engagement against the platen. A rear paper-table 17 may have a forwardly-extending apron 18. A rearwardly-extending track,

whose functions will appear hereinafter, includes two rails 19, which are supported at their forward ends by a bracket 20, fastened to the carriage, and which are supported at their rear ends for lateral movement on instrumentalities, not shown. The parts described so far may be, in general, similar to those disclosed in the patent to William F. Helmond, No. 1,572,139, dated February 9, 1926.

Two carbon-carriers 21 and 22 are mounted on the rails 19 and are separately movable toward and from the platen, and may have the usual adjustable paired side guides 23 and 24, respectively. The front carbon-carrier 21 may have an operating arm 25, and the carbon-carrier 22 may have an operating arm 26 extending forwardly along the arm 25, a short distance to the left of the latter, which arrangement of the arms permits convenient movement of either carbon-carrier independently of the other. The carbon-carriers are provided with usual carbon-holding blades 27.

In one use of my invention, the forward carrier 21 holds carbons 30 interleaved between plies 31 of a main multiple-ply-web A whose top ply may have printed thereon a succession of check-voucher-forms 32 such as are commonly used by municipal governments in paying debts incurred by the municipalities. The lower plies of the web A may bear printed forms corresponding to the check-voucher-forms 32 and disposed thereunder to form sets in a usual way. A form 32 will have a line 33 of record-data characters, which it is desired to manifold on the underlying plies of web A, by carbons 30, and manifolded on each of a plurality of plies 34 of a multiple-ply condensed record-web B, by means of carbons 35 held by the carbon-carrier 22 in interleaved relation with the plies 34, one of the carbons 35 usually being disposed for manifolding the typed matter on the first or outer ply of the condensed record-web. The name and the address of the payee, and other information relative to the purpose of the check-voucher typed on each top ply check-voucher 32, in lines 36, 37 and 38 (Figure 8), may be manifolded on all of the plies 31 of the main web A by means of the carbons 30. It will be understood, as the description proceeds, that only the matter typed in line 33 on the original check-voucher is ordinarily manifolded on the condensed record-web B.

To provide for conveniently passing the check-voucher-web A from a source of supply (not shown) at the rear of the typewriting machine past the carrier 22 to the carrier 21, the blades 27 of the carrier 22 may be elevated above the level of those of the carrier 21 in a way disclosed in my prior Patent, No. 1,600,254, dated September 21, 1926, and the web A passed below the blades 27 of the

5 rear carrier. This construction also holds the condensed record web B above the main web A at the rear of the platen and permits the web A to be moved along the web-course between the rails 19 relative to the web B, without rubbing against the latter.

From the carbon-carriers, the webs A and B pass forwardly between usual side guides 40 supported on a laterally-disposed rod 41 fastened in the brackets 20, and thence downwardly around the platen 11. Two web-holding clamps 42, which may be, in general, like those disclosed in the co-pending application of Alfred G. F. Kurowski, Serial No. 59,456, filed September 30, 1925 (now Patent No. 1,642,248 dated September 13, 1927), are disposed a short distance above the printing line for gripping the sides of the record-web B which extend out beyond the check-voucher-web A against a usual collating paper-table 43. The clamps 42 are mounted for lateral adjustment on a laterally-disposed rock-shaft 44 journaled in forwardly projecting downwardly-inclined members of the 20 platen-displaceable frame 13, which is pivotally mounted on axle-pins 46 held in forwardly projecting side frame-members 47 of the platen-carriage 14. Laterally-disposed work-sheet-gripping ends 48 of the clamps 42 25 are covered with rubber and are normally held, by means to be presently to be described, a short distance in front of the paper-table 43 at the delivery side of the platen against the pull of a spring 50, which has one end fastened to a pin 51 in the left side of the 30 platen-displacing frame 13, and the other end to a pin 52 in a heel 53 of a latch-plate 54 fastened on the rock-shaft 44 by means of a set-screw 55 in a hub 56 fast to the latch-plate.

The shaft 44 is held against lateral displacement in the platen-displacing frame 13 by disposing the latch-plate 54 against the inner surface of the latter at the left side thereof and fastening a collar 57 on the shaft 44 against the inner surface of the frame 13 at the right side thereof. The rock-shaft 44 also supports a web-severing knife 58, which is mounted on two arms 59, each disposed near a clamp 42 and being fastened to a hub 60 loosely mounted upon the shaft 44. Each hub is held against lateral movement away from the adjacent clamp by a collar 61 fastened on the shaft. To keep a cutting blade 62 of the knife 58 far enough away from the table 43 that an operative may easily view, and also manipulate the check-voucher-web, in a way to be presently described, a spring 63 is coiled around the shaft 44 between each arm 59 and the adjacent clamp 42. Each spring is wound to have one end hook over the adjacent clamp and the other end to hook under the adjacent arm and has initial tension to normally swing the knife 58 counterclockwise against

a stop-pin 64 in the right-hand side of the platen-displacing frame 13. The springs 63 and also the spring 50 tend to swing the clamps 42 clockwise against the paper-table 43. This tendency is normally resisted by a tooth 65 of the latch-plate 54 engaging a heel 66 on the forward side of a latch-piece 67, which is pivoted on a pin 68 fast to the platen-displacing frame below the heel 66. The latch-piece 67 has a finger-piece 69 disposed adjacent a finger-piece 70 on a usual control-lever 71 provided for locking the platen-displacing frame 13 down.

In the present invention, a novel feature is embodied in the control-lever 71 by providing a cam-like edge 72 on the lower side of a locking notch 73 which engages around a usual pin 74 in the platen-displacing frame 13. The cam-like edge (Figure 1) is eccentric to the axis of the lever and, as said lever is swung rearwardly on a usual laterally-disposed rock-shaft 75, the edge 72 cams the pin 74 upwardly and raises the platen 11 a small amount to withdraw the latter from engagement with the feed-rolls 15 and 16. The rock-shaft 75 is journaled in the sides of the carriage 14 and carries adjacent the right side of the carriage a latch-piece 76, which may have a notch like that in the lever 71 for engaging a lateral pin 77 fast in the right side of the platen-displacing frame 13. By this construction both ends of the platen are lifted evenly from the feed-rolls 15 and 16 by pushing the lever 71 rearwardly a small amount. The rearward movement of the lever 71 is arrested by the rod 41 before the forward end of the cam-edge 72 passes from under the pin 74. A spring 78 normally urges the lever 71 and the latch-piece 76 into engagement with the pins 74 and 77, respectively, the upper edge of the notch camming said pins downwardly to establish a web-feeding tension for the platen against the feed-rolls. The platen 11 may be rotated by means including a usual finger-wheel 80 and a usual line-spacing mechanism, not shown, which rotating devices operatively connect with the platen-shaft 12 through usual gear-wheels 81, 82 and 83.

As will appear hereinafter, it is advantageous to equip the present typewriting machine with web-collating means including a platen-rotating device 85, which may be in general like that disclosed in the patent to F. L. Morgan, No. 1,280,274, dated October 1, 1918, and may include a gear 86 fast on a usual outer extension 87 of the platen-shaft 12, an operating lever 88 loosely mounted on the shaft-extension, and a drive pawl 89 for operatively connecting said crank and said gear-wheel.

According to one method of using the typewriting machine embodying the present invention, the carbon-interleaved condensed record-web B is passed from the rear of the

5 platen while the latter is disposed in the Figure 6 position, and its leading edges are drawn forward along the paper-table 43 a short distance past the clamps 42, the carbons 35 being disposed in their rearmost positions.

5 The carbons 30 interleaved between the plies of the main or check-voucher-web A may next be positioned to bring them even with the record-sheet-carbons 35.

16 To quickly position both sets of carbons, a usual stop 89^a may be fastened on the right-hand rail 19 at a point to bring the leading edges of the carbons 35 slightly above the printing line when the rear carbon-carrier 22 is pushed back against the stop and the platen lowered. The carbon 30 may be made long enough to come even with the carbons 35 when the carbon-carrier 21 is pushed back against carbon-carrier 22. The line 33 may 20 be collated a short distance behind the leading edges of the carbons so that when the platen is lowered against the feed-rolls 15 and 16, the line 33 will be aligned to the typing position.

25 The side edges of the condenser record-web may pass under side plates 90 fastened adjacent each end of the platen to the platen-displacing frame 13, the plates being curved substantially parallel with the periphery of the 30 platen to be effective for holding the record-web thereagainst. The lower ends of the side plates 90 may be formed with a throat 91 to facilitate passing the record-web under them.

35 To guide the record-web laterally over the paper-table 43, a side guide 92 is fastened on a bar 93, which is fixed on a usual cross-frame 94 between the sides of the platen-displacing frame and extends therefrom upwardly in the rear of the paper-table 43. A cutting-off gage in the form of a cross-rod 95 is fastened to the top of the bar 93 and to the top of a usual upwardly-extending gage-bar 96, which may be fastened to the 45 cross-frame 94 at the right of the bar 93. Another side gage 97 is mounted at the left end of the rod 95. A section 98 is cut out of the bar 93 in position to permit the left-hand guide 40 to extend upwardly past the 50 plane of the paper-table 43. The right-hand side guide 40 may also extend up past the plane of the collating table, and the pair of guides 40 will be effective for controlling the record-web B at both the receiving and the 55 delivery side of the platen. After collating the check-voucher-web A, the position of the leading edge of the first check-voucher-form 32 will be determined by the depth of a space 99 usually provided above the line 33. After 60 typing record-data in line 33, the platen 11 may be line-spaced ahead one or more line-spaces, as will be determined by the spacing desired between the lines on the condensed record-web B, and the finger-piece 69 will be pushed rearwardly and the clamps 42

will become effective to grip the record-web against the paper-table 43. The operator will now press the knife 58 rearwardly, preferably with the thumb of her left hand, until the cutting edge of the blade is disposed a 70 short distance from the table 43. At the same time, the operator can conveniently press the finger-piece 70 rearwardly with the index-finger of her left hand, as indicated in Figure 3. In certain cases, as when a check-voucher-form 32 is short, it may be desirable to press the finger-piece 70 rearwardly before moving the knife adjacent the paper-table 43. Usually the leading edge of a check-voucher will come above the blade. 80 Operation of the finger-piece 70 raises the platen 11 from the feed-rolls 15 and 16, and the operator will now grip the leading end of the main or check-voucher web and draw it upwardly along the paper-table until the typed line 33 aligns with or slightly above the cutting edge of the blade 62. The record-web B will be held stationary by the clamps 42 during advancement of the superposed check-voucher-web A. The blade 62 and the lever 71 will now be released and the platen will be lowered to normal position and both work-webs will be gripped between the platen and the feed-rolls 15 and 16. The latch-piece 67 will be swung forward, and, in a 90 way described in the above-noted application of Kurowski, will be effective to raise the clamps 42 and latch them in their released or ineffective positions. The carbons 95 30 are now positioned in advance of the carbons 35, as indicated by the arrows in Figure 3.

It is required to type data such as a name and an address in the group of lines 36, 37 and 38 (Figure 8) on the check-voucher of the top ply of the main web A at a predetermined distance below the line 33. Since it is desired that the data typed in lines 36, 37 and 38 is not to be copied on the record-web B, it is essential to remove the carbons of the latter from the printing line. The preferred way of doing this in the present invention is to feed the record-web B and its carbons together rearwardly by rotation of the platen 11. Means for doing this quickly include the lever 88 of the condensing device 85, which may be moved forwardly against an adjustable stop-pin 99^a, which can be set to make the condensing device effective to recollate both work-webs A and B rearwardly at one operation so as to bring line 36 to the printing point, as indicated by the intermediate arrow in Figure 4. At the same time, the leading edges of the carbons 35 of the record-web are brought a distance below the printing line, greater than the distance between lines 36 and 38. Also, the line of characters carbon-copied on the record-web, when line 33 was typed, is moved rearwardly adjacent the leading edges of the carbons 35 130

to a position indicated by the lowest arrow in Figure 4. The data to appear in line 36 will now be typed, which will be manifolded on the underlying plies of the check-voucher-web A, whose carbons 30 extend up past the printing line and this data will not be manifolded on the record-web B. The carbons 35 will be advanced toward the printing line as the platen is line-spaced to bring lines 37 and 38 to the printing point, but the distance between lines 36 and 38 is less than the distance of the leading edges of the carbons 35 below the printing point, as shown in Figure 4, and, therefore, the data typed in the lowest line 38 will not be carbon-copied on the record-web B.

As will be understood from the above-noted patent to Morgan, the lever 88 is moved rearwardly as the platen 11 is line-spaced for typing lines 37 and 38 and when the last-named line is typed, the operator will push the lever 88 to the extreme rearward limit of its throw, as indicated by the broken off dotted position in Figure 5, which operation 25 will rotate the platen 11 ahead and the last line of characters, which were manifolded on the record-web B, will be advanced one or more line-spaces above the printing point, as indicated by the lowest arrow in Figure 5. 30 The other four arrows, taken in succession from the top down, shown in Figure 5, indicate the positions of the lines 33, 36, 37 and 38, respectively, on the top-ply of the check-voucher-web A.

35 The clamps 42 will now be operated to grip the condensed record-web B and the platen-displacing frame will be unlocked and swung forwardly in the usual way to the Figure 6 position. The leading edges of the check-voucher-web will be grasped and pulled forwardly to the cut-off gage 95, and the arm 25 pushed rearwardly, which moves both carbon-carriers 21 and 22 rearwardly until the latter strikes the stop 89 on the right-hand rail 40 45 19, the carbons on both carriers being stripped or shifted to new positions between their respective web-plies. In the rearmost position of each carbon-carrier, the leading ends of both sets of carbons 30 and 35 will be aligned, as shown in Figure 6, at a point which will bring them slightly ahead of the printing line of the platen when the latter is swung rearwardly and locked in normal typing position. The knife 58 may now be swung for-

ward until integral stop-fingers 103 at each side of the knife engage against the paper-table 43 and the typed set of forms can be severed from the main web A. The clamps 42 may now be released, and the line 33 on 55 60 the check-voucher-web A typed and manifolded on the plies of the record-web B a line-space distance below the last entry thereon.

In certain cases, the record-web may be 65 much wider than the check-voucher-web and

by means of such arrangement, data may be typed on the record-web which it is not desired to have appear on the check-vouchers.

It will be seen that the invention is adapted for manifolding upon a repetition of forms upon an outer work-web, and also manifolding upon a condensed record-web only a selected portion of the lines which are typed upon said outer work-web; that a plurality of carbon-carriers travel with the carriage, 70 75 one for each web, whereby the top line upon the outer web can be typed and manifolded upon all the web-plies, and then a release may be effected between the platen and its feed-rolls, to permit the outer web to be advanced 80 independently of the inner web; and that at this time means may be set to hold the inner web stationary during such independent advance of the outer web, and the extent of the advance may be gaged. There are also 85 provided a platen-sweep for rotating the platen backwardly after such advance (after the feed-rolls and platen have been restored to co-operative relation), and a stop for said platen-sweep to limit the back stroke of the 90 platen and bring the top web to position for typing the second line thereon. At the same time the inner web is brought to position below the printing field, so that it will not be manifolded, thereby permitting one or 95 more lines to be typed and line-spaced upon the outer web while the inner web remains clear of the typing field. The platen-sweep is connected to advance with the platen, and the platen is also advanceable by means of 100 said sweep, to a limited extent. Said inner web-clamp is also effective to hold the inner web stationary during the platen-displacing and carbon-stripping operation, and a final or tearing-off gage is provided to which the 105 outer web is drawn at the carbon-stripping operation. Said advance gaging means is in the form of a blade movable to position for tearing off the typed form of the web so finally gaged, leaving both webs in position 110 for typing the first line on the next form. The means to gage the extent of independent intermediate advance of the outer web is settable to effective position from normal ineffective position, and serves also as the 115 web-severing blade.

Variations may be resorted to within the scope of the invention, and portions of the improvements may be used without others.

Having thus described my invention, I claim:

1. In a carbon-stripping web-manifolding typewriting machine, in combination, a carriage, a platen around which may be fed a multiple-ply record-web and an outer, narrower multiple-ply work-web printed with a succession of forms, each form bearing space for name and address, said outer work-web being disposed intermediate the side edges of 125 said record-web, a rear extension for said car- 130

riage including a track, two separately-movable carbon-carriers on said track, one disposed behind the other for holding carbons interleaved between the plies of said record-web, the front carbon-carrier holding carbons interleaved between the plies of said outer work-web, typing instrumentalities for typing data on all the plies of both webs, a platen-displacing frame, a paper-table on said frame at the delivery side of said platen, two clamps displaceably mounted on said frame for gripping the side edges of said record-web against said table to hold said record-web stationary without preventing movement of said outer work-web, a gage for positioning the address-space of a form above the carbons of said record-web, means for disposing said clamps in ineffective positions, and reverse feeding mechanism effective for feeding, at one operation, both of said webs and their carbons rearwardly a predetermined amount to bring the carbons of said record-web below the printing line and the first line of said address to the printing line preparatory to typing said address and thereafter severing said form.

2. In a carbon-stripping web-manifolding typewriting machine, in combination, a platen-displacing frame, a platen in said frame around which may be fed an outer multiple-ply work-web interleaved with carbons and overlying a wider multiple-ply carbon-interleaved record-web intermediate the side edges of the latter, said outer work-web having forms printed thereon, each having a space for an address, typing instrumentalities, lower feed-rolls engaging against said platen, means for raising said frame a limited amount to release the grip of said feed-rolls on said webs, a paper-table at the delivery side of said platen, two clamps effective for gripping the side edges of said record-web against said table while said frame is in a raised position and permitting movement of said outer work-web around said platen relative to said record-web, a gage for positioning said address-space above the carbons of said record-web, and mechanism for feeding both work-webs rearwardly a predetermined distance at one operation to bring the carbons of said record-web below the printing line preparatory to typing said address which it is not desired to have copied on said record-web.

3. In a web-manifolding carbon-stripping typewriting machine, in combination, a platen-displacing frame carrying a platen, said frame having forwardly-projecting members at each side, a paper-table supported on said frame at the delivery side of said platen, a laterally-disposed rock-shaft journaled in said forwardly-projecting members, two clamps fast on said rock-shaft for gripping a record-web against said table, two arms loosely mounted on said shaft, one adjacent each

of said clamps and disposed inwardly therefrom, a blade fastened on the ends of said arms for cutting off typed sections of a work-web overlying said record-web, and means for normally holding said blade a short distance in front of said table, said means including two springs wound around said rock-shaft, one spring being disposed between one of said arms and the adjacent clamp, one end of each spring being fastened to the adjacent clamp and the other end fastened to the adjacent blade-supporting arm, the springs having initial tension to urge said blade counter-clockwise, and a stop-member on said platen-displacing frame for arresting said blade at said short distance from said table, said blade being swingable rearwardly away from said stop to cutting-off position adjacent said table.

4. The combination set forth in claim 3 in which means are provided for latching the record-sheet-gripping clamps normally in ineffective positions forwardly from said paper-table, the knife-retaining torsion in said springs being increased thereby.

5. In a web-manifolding typewriting machine, the combination with a carriage, a displaceable frame pivoted at the front of said carriage, feed-rolls on said carriage, and a platen in said frame bearing down upon said feed-rolls for web-feeding, of platen displacing means mounted on said carriage for a rearward movement to forcibly raise said platen from said feed-rolls to release the web, said means being also effective, in a forward movement thereof, to re-lock said frame, and hold the platen and feed-rolls in web-feeding engagement.

6. In a web-manifolding typewriting machine, the combination with a carriage having forwardly extending side elements, a displaceable frame pivoted on said forwardly-extending elements, feed-rolls on said carriage, and a platen in said frame bearing upon said feed-rolls for web-feeding, of means for forcibly vibrating said frame either up or down to control the feeding of the web, including lateral pins in the displaceable frame, and latching means pivotally mounted in said carriage to engage each pin, each latch having a single notch whose upper edge is disposed to engage over its pin, to bind the platen and web-feeding rolls together, and whose lower edge engages under its pin to forcibly separate said platen and said feed-rolls to release the web.

7. In a web-manifolding typewriting machine, the combination with a carriage, having a displaceable frame pivoted at the front of said carriage, and feed-rolls on said carriage, a platen in said frame normally engaging said feed-rolls for feeding the web, of means for raising said platen evenly from said feed-rolls to arrest the feeding of the web, including a lateral pin in each side of

said frame, a rock-shaft on said carriage at the rear of the platen, a release handle having its lower end fast to said rock-shaft adjacent one side of said frame, and an arm fast to said shaft at the opposite side of said frame, said handle and arm having duplicate notches in their edges adjacent said shaft, the lower edges of said notches being formed with cam-faces for engaging under the pins 10 of said frame, to lift the frame and platen free of the feed-rolls, stop means for said handle to prevent said cam-faces from being moved out of the range of said pins, and a spring for holding the notches and pins in 15 engagement.

8. In a web-manifolding typewriting machine having a carriage, and a displaceable platen-frame, and a locking means for said frame, including an upright handle and an 20 arm having their lower ends secured to a shaft rockably mounted on said carriage to engage and disengage with parts of the frame, said handle and arm each having a single notch in the edge thereof, to form opposing cam-faces, one of the cam-faces operative to engage and draw the frame down and the other cam-faces operative to engage the same parts of the frame and lift the platen and frame upward.

30 9. In a web-manifolding typewriting machine, the combination of a carriage, a platen-displacing frame, a platen around which two separate multiple-ply work-webs of different widths may be passed, both webs being interleaved with carbons, the wider work-web being disposed next to the platen to serve as a record-web and extending out on both sides from the overlying narrower web, a track in the rear of said platen and movable laterally 35 therewith, two separately-movable carbon-carriers on said track, one ahead of the other, the rear carbon-carrier holding the carbons interleaved between the plies of said record-web and the forward carrier holding the carbons interleaved between the plies of the outer work-web, a forwardly-swinging paper-table on said platen-displacing frame at the delivery side of said platen, clamps effective for gripping the exposed side edges 40 of said wider work-web against said table when said platen is in normal typing position or in its raised carbon-stripping position, typing instrumentalities for typing a line of record-data on both of said webs, means for 45 raising said platen off the feed-rolls of said machine to permit said outer work-web to be advanced around said platen, said clamps being effective to hold said inner work-webs stationary during the advance of said outer work-sheet, a gage for said outer work-web consisting of a knife which is also effective for 50 severing a typed section from said outer work-web, means for releasing said clamps, and a mechanism for reversely feeding both 55 of said work-webs together rearwardly a

predetermined distance whereby the leading edges of the inner work-web-carbons will be disposed below the printing line and said outer work-web will be brought to position at the printing point for having data typed thereon, which will not be carbon-copied on the inner work-web, said reverse-feeding mechanism being also effective to advance said work-webs together to bring said line of record-data on said inner work-web one 70 line above the printing line, whereby additional record-data typed on a second form or section of said outer web may be carbon-copied on said inner work-web in a condensed form.

10. In a web-manifolding carbon-stripping typewriting machine, the combination with a platen-frame having thereon a displaceable frame carrying a platen, a carriage for said platen-frame, and a rearwardly-inclined paper-table supported on said displaceable frame at the delivery side of said platen, of a laterally-disposed blade for severing a typed section from a work-web fed around said platen, including two arms pivotally 80 mounted upon said displaceable frame and supporting the blade on their outer ends, springs urging said blade away from said table, a stop on the displaceable frame for normally holding said blade against the action of said springs, said blade to be manually pressed downwardly to its web-severing position at the paper-table, and stop means at each end of the blade to engage the paper-table for a web-clearing space under the cutting blade.

11. In a carbon-stripping web-manifolding typewriting machine, the combination with a carriage, having a displaceable frame carrying a platen, a paper-table on said frame at the delivery side of said platen, said frame having downwardly-inclined forwardly-projecting arms, and a shaft in the lower ends of said arms, of a pair of arms swingable on said shaft, a knife-blade joining the free ends of said arms to form a bail, said bail being swingable rearwardly to bring said knife-blade to a position adjacent said table for severing the typed section of a work-web from the main body thereof, a stop-pin on 105 said frame, springs coiled around said shaft to engage each blade-supporting arm for normally pressing said bail against said stop-pin, and a stop on the blade to engage the paper-table and determine the cutting position of the blade.

12. In a carbon-stripping web-manifolding typewriting machine, in combination, a carriage, a platen-displacing frame, a platen around which may be fed two separate work-webs interleaved with carbons, including a multiple-ply record-web and a narrower multiple-ply check-voucher-web overlying said record-web and disposed intermediate the sides thereof, feed-rolls gripping said work- 110 115 120 125 130

webs against the underside of said platen, a rear carriage-extension including a track movable laterally with said carriage, two separately movable carbon-carriers on said track, one ahead of the other, the rear carbon carrier having blades holding the carbons interleaved between the plies of said record-web and the forward carbon-carrier having blades disposed below the planes of the rear carbon-carrier-blades for holding the carbons between the plies of the check-voucher-web, typing instrumentalities for typing a line of record-data on said check-voucher-web, said record-data being carbon-copied on said record-web, a rearwardly inclined paper-table on said platen-displacing frame disposed at the delivery side of said platen and swingable forwardly to substantially horizontal carbon-stripping position, two clamps mounted on said platen-displacing plane for gripping said record-web against said table, said clamps being effective in all positions of said table, rearwardly displaceable instrumentalities effective for raising said platen a limited amount off said feed-rolls to permit a space for a name and an address on the leading check-voucher to be pulled ahead to a gage by the operator's hand, said record-web being held stationary by said clamps, the different elevations of the carbon-holding blades in the two carbon-carriers being effective to reduce the friction resulting from the forward movement of said check-voucher-web relative to said record-web, a pivoted knife-blade movable rearwardly to a position for gaging the advance of said leading check-voucher, means normally holding said knife-blade at a distance from said table when not being used to keep it out of the way of the operator's hand when grasping the leading ends of the check-voucher-web, means for releasing said clamps, and mechanism for reversely feeding both of said work-webs a predetermined distance around said platen to bring the leading ends of the record-web-carbons below the printing line, whereby other data typed on the leading check-voucher will not be carbon-copied on said record-web, said reverse feeding mechanism being also effective when returned to normal position to feed both of said work-webs ahead sufficiently to bring the record-data carbon-copied on said work-web above the printing line, said knife-blade being effective upon movement forwardly against said table for severing a typed set of typed check-voucher-forms from the body of said check-voucher-web after the carbons interleaved therewith have been shifted to a succeeding set of check-voucher-forms.

13. In a device of the class described, in combination, a displaceable platen around which may be fed an outer multiple-ply work-web interleaved with carbons, and a wider multiple-ply record-web interleaved with carbons

bons and extending outwardly from each side of said work-web, two carbon-carriers, one disposed in advance of the other in the rear of said platen, a track on which said carbon-carriers may run, each carbon-carrier being movable independently of the other, means for holding the record-web stationary in any position of said platen, said means permitting movement of said outer work-web, and a knife pivotally mounted in front of said platen and swingable to a position for severing typed sections of said outer work-web at a point above said holding means. 70 75

14. In a web-manifolding typewriting machine, a platen around which may be fed a composite web interleaved with carbons, a carriage, a platen-displacing frame mounted in said carriage, a paper-table at the delivery side of said platen, and a cutting-off knife for said web pivotally mounted in said platen-displacing frame, said knife being normally held in a forward position and movable rearwardly to the cutting off position adjacent said paper-table, said knife having elements for spacing its cutting edge a short distance away from said table. 80 85 90

15. In a web locating and manifolding machine having types, a revoluble platen and line-spacing means, the combination of a carbon-holder for the main web, a separate carbon-holder for a condensed record-web, a web-locating table at the delivery side of the platen, said platen, together with said table, being displaceable for straightening out the webs preparatory to stripping the carbons, a carbon-stripping gage being provided on said table and being displaceable therewith for gaging the leading end of the web at the stripping operation, said condensed record-web being advanced by said line-spacing means preparatory to said carbon-stripping operation, means for clamping the condensed record-web to the table to hold it stationary during a subsequent independent advance of the main web; said clamping means being outside of the field of the condensed record-carbons to leave them movable, and a gage upon said table for locating the leading end of the independently advanced main web relatively to the condensed record-web. 100 105 110 115

16. In a web locating and manifolding machine having types, a revoluble platen and line-spacing means, the combination of a carbon-holder for the main web, a separate carbon-holder for a condensed record-web, a web-locating table at the delivery side of the platen, said platen, together with said table, being displaceable for straightening out the webs preparatory to stripping the carbons, a carbon-stripping gage being provided on said table and being displaceable therewith for gaging the leading end of the web at the stripping operation, said condensed record-web being advanced by said line-spacing means preparatory to said carbon-stripping opera- 120 125 130

tion, means for clamping the condensed record-web to the table to hold it stationary during a subsequent independent advance of the main web; said clamping means being outside of the field of the condensed record-carbons to leave them movable, a gage upon said table for locating the leading end of the independently advanced main web relatively to the condensed record-web, and means for rotating the platen backwardly to restore the advanced main web to the desired typing position, and at the same time to remove the condensed record-web from the typing field.

17. In a web-manifolding machine having types and a revoluble platen, displaceable for straightening out the webs preparatory to stripping the carbons, the combination of a carbon-holder for a main web, an independent carbon-holder for a condensed record web, a collating table for both webs mounted at the delivery side of the platen and having a side edge gage, a gage for the leading edge of the main web, means for severing the main web when so gaged, said end gage and severing means being so positioned that the first untyped form on the main web is left in correct position to type the first line thereon, a platen-rotator connectible with the platen, means for connecting said rotator to said platen to rotate the same backwardly until the condensed record web is withdrawn from the printing field on the platen, and also including a stop for said rotator to limit such withdrawal, the platen having releasable paper-feeding means which, when released, permit the main web to be pulled up over the stationary condensed record web, a releasable clamp being provided for detaining the condensed record web while the main web is being pulled thereover, a gage whereby the independent advance of the main web may be determined, said stop arresting the rotator and platen when the condensed record carbon have been withdrawn from the printing field, and line-spacing mechanism for the platen, said rotator being advanced with the platen by means of said line-spacing mechanism while typing is being done upon the main web and omitted from the condensed record web, said rotator being capable, after the conclusion of such typing and line feeding, of advancing the platen sufficiently to bring the condensed record web to position to type a line thereon beneath its previously typed line.

18. A typewriting machine for manifolding upon a repetition of forms upon a work-web and also manifolding upon a condensed record-web only a selected portion of the lines which are typed upon said work-web, including a carriage having a platen and feed-rolls, a plurality of carbon-carriers traveling with said carriage, one for each web, whereby the top line upon the outer web can be typed and manifolded upon all the web-plies, means to effect release between the

platen and the feed-rolls to permit the outer web to be advanced independently of the inner web, means settable to hold the inner web stationary during such independent advance of the outer web, and means to gage the extent of independent advance of the outer web.

19. A typewriting machine for manifolding upon a repetition of forms upon a work-web and also manifolding upon a condensed record-web only a selected portion of the lines which are typed upon said work-web, including a carriage having a platen and feed-rolls, a plurality of carbon-carriers traveling with said carriage, one for each web, whereby the top line upon the outer web can be typed and manifolded upon all the web-plies, means to effect release between the platen and the feed-rolls to permit the outer web to be advanced independently of the inner web, means settable to hold the inner web stationary during such independent advance of the outer web, means to gage the extent of independent advance of the outer web, a platen-sweep for rotating the platen backwardly after such advance when the feed-rolls and platen have been restored to co-operative relation, a stop for said platen-sweep to limit the back stroke of the platen and bring the top web to position for typing the second line thereon, and the inner web to position below the printing field, so that it will not be manifolded, thereby permitting one or more lines to be typed upon the outer web while the inner web remains clear of the typing field, said platen-sweep connected to advance with the platen, and the platen being also advanceable by said sweep, and means for limiting the extent to which the platen-sweep advances the platen.

20. A typewriting machine for manifolding upon a repetition of forms upon a work-web and also manifolding upon a condensed record-web only a selected portion of the lines which are typed upon said work-web, including a carriage having a platen and feed-rolls, a plurality of carbon-carriers traveling with said carriage, one for each web, whereby the top line upon the outer web can be typed and manifolded upon all the web-plies, means to effect release between the platen and the feed-rolls to permit the outer web to be advanced independently of the inner web, a clamp settable to hold the inner web stationary during such independent advance of the outer web, and means to gage the extent of independent advance of the outer web, said platen being mounted for displacement to straighten out the webs preparatory to stripping the carbons, said inner web-clamp being also effective to hold the inner web stationary during the carbon-stripping operation, a tearing-off gage being provided to which the outer web is drawn at the carbon-stripping operation, said advance

gaging means in the form of a blade movable to position for tearing off the typed form of the web so gaged, leaving both webs in position for typing the first line on the next form.

21. A typewriting machine for manifolding upon a repetition of forms upon a work-web and also manifolding upon a condensed record-web only a selected portion of the lines which are typed upon said work-web, including a carriage having a platen and feed-rolls, a plurality of carbon-carriers traveling with said carriage, one for each web, whereby the top line upon the outer web can be typed and manifolded upon all the web-plies, means to effect release between the platen and the feed-rolls to permit the outer web to be advanced independently of the inner web, a clamp settable to hold the inner web stationary during such independent advance of the outer web, means to gage the extent of independent advance of the outer web, a platen-sweep for rotating the platen backwardly after such advance when the feed-rolls and platen have been restored to co-operative relation, a stop for said platen-sweep to limit the back stroke of the platen and bring the top web to position for typing the second line thereon, and the inner web to position below the printing field, so that it will not be manifolded, thereby permitting one or more lines to be typed upon the outer web while the inner web remains clear of the typing field, said platen-sweep connected to advance with the platen, and the platen being also advanceable by said sweep, and means for limiting the extent to which the platen-sweep advances the platen, said platen being mounted for displacement to straighten out the webs preparatory to stripping the carbons, said inner web-clamp being also effective to hold the inner web stationary during the carbon-stripping operation, a tearing-off gage being provided to which the outer web is drawn at the carbon-stripping operation, said advance gaging means in the form of a blade movable to position for tearing off the typed form of the web so gaged, leaving both webs in position for typing the first line on the next form.

22. A typewriting machine for manifolding upon a repetition of forms upon a work-web and also manifolding upon a condensed record-web only a selected portion of the lines which are typed upon said work-web, including a carriage having a platen and feed-rolls, a plurality of carbon-carriers traveling with said carriage, one for each web, whereby the top line upon the outer web can be typed and manifolded upon all the web-plies, means to effect release between the platen and the feed-rolls to permit the outer web to be advanced independently of the inner web, means settable to hold the inner web stationary during such independ-

ent advance of the outer web, and means to gage the extent of independent advance of the outer web, said gaging means settable to effective position from normal ineffective position, and severing also as a web-severing blade.

JESSE A. B. SMITH.
